COLLAPSIBLE CAP OR THE LIKE

Robert Dorfman, 165 E. 35th St., New York, N.Y.

Filed June 20, 1961, Ser. No. 65,653

Term of patent 7 years

(Cl. D3—13)

Fig. 1

Fig. 2

FIG. 1 is a top plan view of a collapsible cap or the like showing my new design; and

FIG. 2 is a side elevational view thereof.

I claim:

The ornamental design for a collapsible cap or the like, as shown.
